UNITED STATES PATENT OFFICE.

CHRISTIAN MOMBERG, OF CHICAGO, ILLINOIS.

MATCHED FLOORING.

No. 890,436.

Specification of Letters Patent.

Patented June 9, 1908.

Application filed October 11, 1907. Serial No. 397,003.

To all whom it may concern:

Be it known that I, CHRISTIAN MOMBERG, a citizen of the United States, and resident of Chicago, county of Cook, and State of Illinois, have invented certain new and useful Improvements in Matched Flooring, of which the following is a specification, and which are illustrated in the accompanying drawings, forming a part thereof.

10 The invention relates to wooden flooring wherein the meeting edges of adjacent boards or strips have intercalating tongues and grooves for providing a firm joint, the opposite marginal edges of each strip being of complementary form in order that, in building a floor, each strip, if properly placed, may be fitted with any other of similar form.

More particularly, the invention relates to flooring of that type in which the marginal edges of the strips are so formed that a groove is provided having flaring walls, and into which, therefore, a tongue of substantially complementary form may be fitted with ease.

25 The object of the invention is to provide a flooring of such improved form that it may be readily manufactured in such machines as are now employed for the production of flooring, that its intercalating parts may be easily 30 fitted together to form a firm joint but little affected by a wearing away of the upper surface of the floor for a considerable depth, while in each strip provision is made for the driving of nails for securing the flooring in 35 position at such a point that a splitting out of the wood is not likely to be effected.

In the accompanying drawings,—Figure 1 is a perspective view showing a detail of wooden flooring embodying the invention; 40 Fig. 2 is a sectional view of the flooring, and shows a detail of a supporting member therefor; and Fig. 3 is similar to Fig. 2, but shows a slight modification in the construction.

The flooring provided by the invention is 45 preferably made in strips as 10, 11, 12, the longitudinal marginal edges, as 13, 14, of the strips being of complementary form to mate or match with the meeting edges of adjacent strips. As shown, the edges 13, 14 of the 50 strips 10, 11 and 12 have a tongue 15 and groove 16, respectively.

In carrying out the invention, the mouth of the groove 16 is made flaring by inclining the edge 14 above and below the groove, as 55 indicated at 17, 18, the incline 18 above the

groove being, however, preferably terminated at 19, and the remaining portion 20 of the marginal edge 14 being inclined in the reverse direction in the particular forms of construction illustrated in the drawings. 60

The marginal edge 13 of each of the strips of flooring is substantially complementary in form to that just described, there being oppositely inclined portions 21, 22 above and below the tongue 15 at its base, while, as 65 shown, the incline 21 above the tongue is reversed, as indicated at 23. Preferably, the inclined portion 20 of the edge 14 is somewhat steeper than the corresponding portion 23 of the edge 13, in order that adjacent 70 strips when fitted together may contact first at the surface of the flooring produced. This feature of the construction is somewhat exaggerated in the drawings for the purpose of illustration. 75

The construction provides a tongue and groove having the usual width of contacting surface, whereby a firm joint is effected, while by reason of the flaring mouth provided for the groove 16, the difficulty heretofore encountered in fitting matched flooring having a tongue and groove is avoided. 80

Nails 24 for securing the floor to a suitable support, as the joist 25, may be entered upon the surface 21, there being less liability of 85 splitting the material from which the flooring is formed if nails are entered upon such a surface than if entered at the base of an abrupt angular turn in the surface. Furthermore, by the flaring form provided at the base of 90 the tongue 15, that part of the strip through which the nail passes has sufficient body to prevent the splitting off of the tongue by the driving of the nail. By reason of the forwardly inclined portion 23 provided upon the 95 marginal edge 13 above the tongue, the effective width of the strip is but little reduced in the formation of the tongue, while the invention further provides a construction of flooring in which the tongue and grooves of meeting edges may be sufficiently remote from the 100 surface of the floor to permit of a wearing away of the floor to a considerable depth without reducing the strength of the joints.

If desired, the meeting edges 13, 14 of the 105 strips 10, 11, 12 may be rounded at the base of the tongue 15 and adjacent the mouth of the groove 16, as indicated at 26, 27, Fig. 3.

I claim as my invention,—

1. In combination, two floor members, a 110

- 2
- marginal edge of one of the members being longitudinally grooved and backwardly inclined above the groove, the top and bottom walls of the groove being substantially horizontal adjacent the base of the groove and flaring adjacent the mouth of the groove, and a marginal edge of the other floor member being substantially complementary in form.
- 10 2. In combination, two floor members, a marginal edge of one of the members being longitudinally grooved and backwardly inclined above the groove, the top and bottom walls of the groove being substantially horizontal adjacent the base of the groove and flaring adjacent the mouth of the groove, the flaring bottom wall of the groove being continued to the lower surface of the floor member, and a marginal edge of the other floor member being substantially complementary in form.
- 15 3. In combination, two floor members adapted to be juxtaposed in service, the contacting face of one of the members being beveled and provided intermediate its upper and lower marginal edges with a tongue, the parts of the beveled face above and below the tongue being substantially parallel but out of alignment and the contacting face of the other floor member being substantially complementary in form.
- 20 4. In combination, two floor members adapted to be juxtaposed in service, the contacting face of one of the members being beveled and provided intermediate its upper and lower marginal edges with a tongue, the parts of the beveled face above and below the tongue being substantially parallel but out of alignment and the contacting face of the other floor member being substantially complementary in form.
- 25 5. In combination, two floor members adapted to be juxtaposed in service, the contacting face of one of the members having a projecting tongue, the upper face of the tongue being substantially horizontal adjacent its point and upwardly inclined adjacent its base to provide a nailing surface, and the contacting face of the other member being substantially complementary in form.
